POWER LIFT FOR GIN BREASTS

George H. McClintock, Refugio, Tex.

Application February 29, 1936, Serial No. 66,444

4 Claims. (Cl. 192—139)

This invention relates to gin breast lifting devices, and has for one of its objects the production of a power device for automatically lifting the breast of a cotton gin through the operation of a trigger mechanism, whereby the breast may be lifted out of a ginning position should the gin become choked or otherwise fail to properly function.

A further object of this invention is the production of a simple and efficient power mechanism for lifting the breast of a cotton gin and also automatically applying a brake to the power mechanism and re-setting the same, whereby the power mechanism will again be in a position to lift the breast should the necessity for such action again arise.

Another object of this invention is the production of a simple and efficient mechanism for lifting the breast of a cotton gin which is so constituted as to operate with facility in conjunction with the conventional gin structure now so commonly in use.

Other objects and advantages of the present invention will appear throughout the following specification and claims.

In the drawings:

Figure 1 is a side elevation of the power device shown in association with a cotton gin;

Figure 2 is a top plan view of the power device shown in Figure 1;

Figure 3 is a front end elevation of the power device, the weight-supporting lever being shown in section and a portion of the gin being also shown;

Figure 4 is a transverse section taken on line 35 4—4 of Figure 2;

Figure 5 is a perspective view of a portion of the trigger-supporting frame and trigger mechanism;

Figure 6 is a section taken on line 6—6 of Figure 3;

Figure 7 is a top plan view of the forward end of the power mechanism, the parts being shown in their operating position.

By referring to the drawings, it will be seen that G designates the gin which may be of the conventional type having a conventional gin breast B which is pivotally mounted in the conventional manner and is actuated by a pivot cam 50 lift L also of the conventional type. This cam lift L is actuated by an operating rod 19 which extends rearwardly of the gin G, as shown clearly in Figure 1;

For the purpose of lifting the gin breast B, I 55 employ a specially constructed power lift mecha-

nism A, which power lift mechanism comprises a frame 11 upon which frame is the main drive shaft 12 carrying a drive pulley 13 which is actuated by a drive belt 14 from a power line shaft. This drive shaft 12 carries a second driving pulley 15 over which a power belt 16 passes, the power belt 16 extending forwardly and longitudinally of the frame A and passing around an idle pulley 17 supported or carried by the transmission shaft 18. A fixed or drive pulley 19 is carried by the transmission shaft 18 and is secured thereto in the conventional manner, the drive pulley 19 being arranged in close proximity and to one side of the idle pulley 17.

A brake drum 20 is also carried by and secured to one side of the fixed pulley 19. A brake band 21 is secured at one end to the supporting rod 22 which supporting rod 22 is in turn supported by the upstanding arms 23 carried by the frame 11. The opposite end of the brake band 21 is secured to the inner end of the brake lever 25, which brake lever is pivotally secured between the bifurcated end 26 of the standard 27 mounted on the front end of the frame 11. A suitable counterbalance weight 28 is carried by the outer end of the brake lever 25.

The frame 11 carries near its forward end in advance of the transmission shaft 18 an auxiliary transmission shaft 29 which extends substantially 30 parallel to the transmission shaft 18 and is journaled upon the journals 30 carried by the frame 11. This auxiliary transmission shaft 29 carries a sprocket wheel 31 over which passes a sprocket chain 32, the sprocket chain 32 passing 35 also over the sprocket wheel 33 carried by the transmission shaft 18 whereby rotary motion may be imparted from the transmission shaft 18 to the auxiliary shaft 29. The auxiliary transmission shaft 29 carries a gear 34 at its outer end 40 which meshes with an enlarged gear 35, which gear 35 is carried by the actuating shaft 36 which is journaled at one end, as at 37, to the frame 11, and at its opposite end to a suitable supporting journal 38. This actuating shaft 36 45 carries an actuating arm 39 which in turn connects to the operating rod 10, which rod 10 is connected to the cam lifting lever L. A hand lever 40 is also carried by the actuating shaft 36 50 to permit the manual operation of the shaft 36 should it be desired at any time.

A chain of other suitable flexible element 41 is connected to a connecting hook 42 carried by the enlarged gear wheel 35 and this gear wheel also carries a plurality of connecting hooks 43 which 55

act as guides or cradles for the chain as the gear operates in a clockwise direction. This chain 41 is connected at its rear end to a lever 44, which lever 44 is carried by an upstanding rod 45—note 5 Figure 5—the upstanding rod 45 being journaled at its respective ends upon the arms 46 of the upright frame 47. This upright shaft 45 carries a belt shifting arm 48 near its lower end which engages the belt shifting finger 49, the belt shifting finger 49 also engaging or straddling the belt 16 for the purpose of shifting the belt 16 from the idle pulley 17 to the driving or fixed pulley 19. A tripping lever 50 is secured to the upper end of the upright shaft 45, and this tripping lever 15 is attached to a tension coil spring 51 which spring is in turn connected to a point near the rear end of the frame 11, as at 52, to normally exert a rearward pulling action upon the tripping lever 50. A trigger 53 is pivotally secured 20 to the tripping lever 50 and is adapted to normally engage the notch 54' formed in the top of the upright frame 47 and hold the parts in a set or inactive position. A coil spring 55 is connected to the outer end of the trigger 53 and also 25 to the tripping lever 50 to normally hold the trigger 53 in an engaging position. A pull cord 54 is connected to the outer end of the trigger 53 whereby a pull manually or otherwise upon the cord 54 will cause the trigger 53 to become disengaged from the notch 54', the coil spring 51 causing the tripping lever 50 to be pulled rearwardly, the shaft 45 to be rotated, the lever 44 to be swung, thereby shifting the belt 16 from the loose pulley 17 to the driving or fixed pulley 19 and 30 causing the parts to move from the position shown in Figure 2 to the position shown in Figure 7.

In conjunction with my device, I employ a 40 brake controlling mechanism which consists in a vertically extending rod 60 which is journaled upon suitable journals 61 carried by the front of the frame 11. This rod 60 is provided with an angularly extending finger 62 which is adapted to extend under the brake actuating lever 25. A 45 second angularly extending finger 63 is carried near the lower end of the rod 60 and extends in an opposite direction to the finger 62 so that this finger 63 may be engaged by the lug 64 carried by the inner face of the enlarged gear wheel 35. A 50 coil spring 65 is connected to an arm 66 carried by the rod 60 and normally tends to pull the finger 62 in toward the front end of the frame 11 and under the lever 25.

The operation of the device is as follows:—

55 When the trigger is set for holding the arm 50 in a set position and the operating cable or pull cord 54 is pulled, the trigger 53 will be disengaged from the notch 54' and the spring 51 will swing the arm 50 rearwardly, the finger 62 being in a 60 position under the lever 25 to release the brake band 21 and the driving belt 16 being in engagement with the idle pulley 17. The parts will then immediately assume the position shown in Figure 7 due to the fact that the brake will be 65 disengaged and the gear wheel 35 may rotate in a counter-clockwise direction under the pull of the lever 44 on the chain 41. At this instant the belt shifting finger 49 will immediately throw the belt 16 from the position shown in Figure 2 70 to the position shown in Figure 7 whereupon the driving pulley 19 will be actuated to gradually pull upon the chain 41 through the rotation of the gear wheel 35 in a clockwise direction and this movement as it continues will cause a pull upon 75 the rod 10 and the opening of the gin breast. As

this rotation of the wheel 35 continues, the lug 64 will engage the finger 63 and the finger 62 to the dotted line position shown in Figure 2, whereupon the weighted lever 25 will cause the brake band 21 to be applied slowing down the rotation of the shaft 18 and the lever 44 through the pull of the chain 41 will pull the arm 50 and trigger 53 to a set position such as is shown in Figure 5, resetting the various parts whereby they may again actuate upon the pull of the cord 54 to release the trigger.

It should be understood that certain detail changes in the mechanical construction, combination and arrangement of parts may be employed without departing from the spirit of the invention, so long as such changes fall within the scope of the appended claims.

Having described the invention, what is claimed as new is:

1. A power mechanism for automatically lifting a gin breast comprising a frame, a driving means carried by the frame, a transmission means carried by said frame, an auxiliary transmission means also carried by the frame, an actuating shaft carried by the frame, an operating gear wheel carried by said actuating shaft, driving means interposed between said gear wheel and said first mentioned transmission means, a driving element connecting the transmission means with the driving means, means for shifting said driving element to and from a clutching position, a trigger for holding said last mentioned means in a set position, a tension spring connected to said shifting means, flexible means connecting said gear wheel with said shifting means for automatically returning the shifting means to a set position, spring means engaging said trigger for holding the trigger in a locked position, and means for facilitating the moving of said trigger to a released position.

2. A power device of the class described comprising a frame, a driving mechanism carried by the frame, a transmission mechanism carried by the frame, said transmission mechanism comprising an idle pulley and a fixed pulley, an auxiliary transmission shaft driven from said transmission means, and actuating shaft for opening and closing a gin breast, a driving gear carried by said actuating shaft and driven from said auxiliary transmission shaft, a brake mechanism for said transmission mechanism, a tripping mechanism for releasing said brake mechanism, and means carried by said gear for moving said tripping mechanism to a position for releasing said brake mechanism.

3. A power device of the class described comprising a frame, a driving mechanism carried by the frame, a transmission mechanism carried by the frame, said transmission mechanism comprising an idle pulley and a fixed pulley, an auxiliary transmission shaft driven from said transmission means, an actuating shaft for opening and closing a gin breast, a driving gear carried by said actuating shaft and driven from said auxiliary transmission shaft, a brake mechanism for said transmission mechanism, a tripping mechanism for releasing said brake mechanism, means carried by said gear for moving said tripping mechanism to a position for releasing said brake mechanism, said brake mechanism having an operating weighted lever, said tripping mechanism comprising a rod having a laterally extending finger for engaging said lever and releasing said brake mechanism as the finger engages said lever, means for normally

holding said finger in engagement with the lever, said tripping mechanism also comprising an oppositely extending finger, and said gear having a lug for engaging the last mentioned finger whereby said tripping mechanism will be moved to a position for disengaging said lever when said gear rotates to a predetermined position.

5 4. A power device of the class described comprising a frame, a driving mechanism carried by the frame, a transmission mechanism carried by the frame, said transmission mechanism comprising an idle pulley and a fixed pulley, an auxiliary transmission shaft driven from said transmission means, an actuating shaft driven from said auxiliary transmission shaft, means connected to said actuating shaft for operating a gin breast, a brake mechanism for said gin breast, the means for driving the actuating shaft from the

auxiliary transmission shaft embodying a gear wheel, a chain secured to said gear wheel, guiding means for the chain, a belt for driving the transmission mechanism from the driving mechanism, a belt shifting mechanism for moving the belt to and from a driving to an idle position, said shifting mechanism comprising an operating shaft and means for engaging the belt, an operating lever engaging said last mentioned shaft, tension means for automatically swinging the lever, latching means for holding said lever in a locked position, means for releasing the latch whereby the lever may swing automatically for shifting said belt, and means for connecting the chain to said last mentioned shaft for returning said lever from an unlocked to a locked position.
